CLAIM

We claim the ornamental design for a disposable intubation apparatus, as shown and described.

DESCRIPTION

FIG. 1 is a front, bottom, right side perspective view of a disposable intubation apparatus, showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a front, top, left side perspective view thereof; FIG. 9 is an enlarged view showing a portion from FIG. 1; FIG. 10 is an enlarged view showing a portion from FIG. 2; FIG. 11 is an enlarged view showing a portion from FIG. 3; FIG. 12 is an enlarged view showing a portion from FIG. 4; FIG. 13 is an enlarged view showing a portion from FIG. 5; FIG. 14 is an enlarged view showing a portion from FIGS. 7; and,

FIG. 15 is an enlarged view showing a portion from FIG. 8. The broken lines in the drawings depict portions of the disposable intubation apparatus and illustrate the enlarged elements thereof, and form no part of the claimed design.

1 Claim, 14 Drawing Sheets
